UNITED STATES PATENT OFFICE

EDWARD N. JACOBI, OF MILWAUKEE, WISCONSIN, ASSIGNOR TO BRIGGS & STRATTON CORPORATION, OF MILWAUKEE, WISCONSIN, A CORPORATION OF DELAWARE

LOCK

Application filed December 24, 1930. Serial No. 504,549.

This invention relates to certain new and useful improvements in locks and refers more particularly to tumbler locks.

The majority of tumbler locks now in use 5 may be divided into two well defined classes. In one the tumblers are round pins and in the other they are stamped from flat stock; and this invention is especially directed to the latter.

10 Heretofore it has been difficult in flat tumbler type locks to obtain the strength necessary to meet the Insurance Underwriter's strength test, and this invention therefore contemplates and has as one of its 15 objects the provision of a flat tumbler type lock in which the arrangement of the tumblers and their construction, and the disposition of the metal of the cylinder or plug, is such that neither the tumblers nor the cylinder can be broken by any tool that can be applied when the lock is in its regular casing.

Numerous manufacturing difficulties were also entailed by the design of the flat type 20 tumbler locks heretofore employed, for the construction of their cylinders necessitated the provision of two cores in each die to form the tumbler receiving slots which had to be pulled in opposite directions. This obviously increased the cost of forming the 25 cylinders.

Hence it is another object of this invention to simplify the manufacture and materially reduce the cost of locks of this type.

Another object of this invention resides 30 in the provision of a lock structure of the character described wherein the assembling of the cylinders may be split up into different operations and permitting assembling by means of automatic machines.

35 The thin walled sections between the tumblers, of locks of this character heretofore in use, by reason of the fact that their cylinders were formed by die casting, were affected by corrosion, and tended to cause 40 binding after the locks were in service a length of time.

This invention therefore has as another of 45 its objects the provision of a lock of the character described in which the tumbler receiving recesses or guides are all connected

and form substantially one enlarged chamber in the cylinder so that no thin walled sections are required.

Another object of this invention resides in the construction of the tumblers whereby 55 forming dies of more rugged construction are possible.

And a further object of this invention is to generally simplify and improve the construction of the tumbler locks. 60

With the above and other objects in view which will appear as the description proceeds, my invention resides in the novel construction, combination and arrangement of parts substantially as hereinafter described and 65 more particularly defined by the appended claims, it being understood that such changes in the precise embodiment of the herein disclosed invention may be made as come within the scope of the claims. 70

In the accompanying drawings, I have illustrated two complete examples of the physical embodiment of my invention constructed according to the best mode I have so far devised for the practical application of the principles thereof, and in which: 75

Figure 1 is a view of a lock cylinder embodying my invention and taken so as to show the top of the tumblers;

Figure 2 is a sectional view taken through 80 Figure 1 on the plane of the line 2—2 and showing the tumblers retracted by means of a key;

Figure 3 is a view similar to Figure 1 and illustrating the bottom of the tumblers; 85

Figure 4 is a cross sectional view taken through Figure 2 on the plane of the line 4—4;

Figure 5 is a cross sectional view similar 90 to Figure 4 taken through Figure 2 on the plane of the line 5—5, but without the key;

Figure 6 is a detailed perspective view of one of the tumblers; and

Figure 7 is a perspective view illustrating 95 a tumbler of slightly modified construction.

Referring now more particularly to the accompanying drawings in which like numerals designate like parts throughout the several views, the numeral 7 represents a cylindrical lock cylinder or plug having an enlarged 100

head 8 at its forward end. The back of the enlarged head is partially cut away as at 9, to provide a pair of abutments 10 which co-operate with abutments on the lock cylinder 5 mounting head or casing, not shown, to define the limits of rotation of the cylinder therein.

Projected from the opposite end of the cylindrical plug is an eccentric cam 11 to impart movement to whatever mechanism the lock is employed with, and an annular groove 12 having an entrance opening or slot 14 communicating therewith for retaining the plug in its casing or mounting head, not shown. 10 Extended inwardly from the front of the cylinder is a key-way 15, the outer end of which is flared outwardly, as at 16, to facilitate the insertion of a proper key 17 and the inner end of which terminates at a point spaced 15 from the annular groove 12.

Between the enlarged head 8 and the inner end of the key-way and in communication therewith, is a transverse opening or chamber 18 of irregular shape and it is noted that the 20 key-way 15 is not centrally located, but is positioned to one side of the longitudinal axis of the cylinder and that the chamber or opening 18 extends to the opposite side of the longitudinal axis.

25 The opening 18 includes a plurality of transverse substantially rectangular slots 19 formed entirely through the plug to slidably receive locking tumblers 20. At one end of the transverse slots 19 the major portion of the metal between the slots is cut away so that at this side of the cylinder, see Figure 1, a 30 continuous opening having a number of opposed grooves in its opposite sides is formed, the opposed grooves being the sides of the slots 19.

At the opposite ends of the slots 19 and from a point in line with the adjacent edge of the key-way, which may be considered its bottom, the metal between the slots is cut away 45 only from a point in line with the key-way to substantially the opposite side wall, so that the remaining portions 21, best shown in Figures 3 and 4, form a continuation of the bottom of the key-way and provide a rest for the key.

50 The tumblers, see Figure 6, are formed of substantially flat stock and have a medial longitudinal reinforcing rib or bulge projecting from each face to provide portions 22 of increased thickness, extending throughout their length. At one side of the bulge or enlarged middle portion 22, the metal is cut away, as at 23 to provide a key receiving recess, the position of which with respect to the 55 length of the tumbler controls the formation of the bit of the key. Two very important advantages obtained with this construction of the tumblers are an exceptionally strong tumbler and a rugged tumbler forming die.

60 At the sides of the tumblers opposite their

cutaway portions 23 are webs 24 which co-operate with an abutment 25 formed in the plug in communication with the tumbler receiving chamber, to limit their outward movement as will be later described, and at one 65 end of each tumbler is a sidewise directed lug 26 for a purpose to be later described.

The faces of the tumblers between their longitudinal enlargements or bulges 22 and their webs 24, are so shaped as to form round bottomed longitudinal grooves 27, and the grooves of adjacent tumblers cooperate to define guides or wells for expansive springs 28 which yieldably urge the tumblers outwardly of the plug.

70 In assembling the tumblers with the plug, their ends having the sidewise struck lugs 26 are inserted first and the tumblers are inserted from that side of the plug at which the metal between the tumbler receiving slots 19 is cut away. The tumblers thus drop down into their respective grooves until the leading end 29 of their elongated webs 24 strikes the abutment 25, see Figure 5.

75 The springs 28 are then inserted in the wells defined by the adjacent round bottomed grooves of adjacent tumblers so that their inner ends rest on top of the sidewise directed lugs 26 of the tumblers which, as best illustrated in Figure 3, are so disposed as to be aligned with the lower ends of the springs.

80 All of the springs with the exception of the one nearest the enlarged head 8 of the plug are confined between adjacent tumblers, and the said spring adjacent the enlarged head is 85 guided by the cooperation of the groove of its tumbler and the adjacent end of the opening 18 which is formed as at 30, to conform to the shape of the spring.

85 After the springs have been properly positioned, pins 31 are secured in transversely extending recesses 32 in line with and above the ends of the springs so as to confine the springs within the plug and afford an abutment between which and the sidewise directed lugs 26 of the tumblers they are confined.

90 The cross pins 31 may be secured in their respective transverse slots in any desired manner and in the present instance are held by swedging the material of the plug, as at 95 33, over the pins.

95 All of the tumblers are thus yieldably urged to project their ends having the sidewise directed lugs 26 outwardly of the plug as in Figure 5 and such outward movement of the tumblers is limited by the engagement of the lower end 29 of their elongated webs 24 with the plug abutment 25.

100 It is noted that the enlarged portions 22 of the tumblers and their urging springs 28 are all disposed to that side of the longitudinal axis of the plug opposite the side in which the key-way 15 is formed so that the 105 cut away portions 23 of the tumblers are aligned with the key-way. The upper or 110

serrated edge of the key when inserted in the slot thus engages the upper edges 34 of the cut away portions 23 and lifts each tumbler against the action of its urging spring 5 to retract the same within the periphery of the plug.

The tumbler shown in Figure 7 is substantially similar to that described and shown in Figure 6, except that the abutment with 10 which the spring engages is formed by striking a medial portion of the tumbler outwardly to one side as at 26'.

From the foregoing description taken in connection with the accompanying drawings 15 it will be readily apparent to those skilled in the art to which this invention relates, that the strength of a tumbler lock constructed in accordance with my invention is considerably increased without in any way adding to its external dimensions. The tumblers, particularly, are stronger, their increased rigidity being obtained principally from the medial longitudinal enlargement or 20 bulge which serves as a stiffening rib and by reason of the fact their construction permits them to be formed of heavier material. The increased thickness of the tumblers also affords greater contact area with the mounting member abutments.

30 It is also apparent that an appreciable saving may be effected in manufacture of locks embodying this invention for the tumbler forming dies may be of more rugged construction than heretofore possible, which obviously lengthens their useful life, and the 35 design of the opening in the plug in which the tumblers are received being such as to permit the same to be formed by a single core which may be pulled in one direction permits a greater number of molds in a single 40 cylinder forming die. Assembling of the tumblers with the cylinder is also greatly facilitated. This operation can be split up into a tumbler assembling and spring assembling 45 operation performed by different operators or if desired the assembling may be done by automatic machines.

The fact that the opening in the cylinder or plug has no thin walled sections is also 50 an important advantage, in that binding of the tumblers due to corrosion is entirely obviated.

What I claim as my invention is:

1. In a lock cylinder of the character described, a plurality of spaced locking tumblers mounted for movement transverse to the axis of the lock cylinder, a plurality of supports fixedly mounted in said lock cylinder intermediate said tumblers and expansive 55 springs seated on said supports and disposed between adjacent tumblers for yieldably urging the same to outermost position.

2. In a lock cylinder of the character described, a plurality of spaced locking tumblers mounted for movement transverse to 60

the longitudinal axis of the lock cylinder, a plurality of supports fixedly mounted in said lock cylinder intermediate said tumblers, yieldable means seated on said supports and normally urging the tumblers to outermost 70 position, and means on said tumblers providing guides for the yieldable urging means.

3. In a lock cylinder having a key-way, tumblers slidably disposed in the lock cylinder with one side portion thereof in alignment with the key-way, said side portions of the tumblers in alignment with the key-way being medially cut away to provide key receiving recesses, and reinforcing means 75 extending longitudinally on the tumblers between the key receiving recesses and the opposite sides thereof.

4. In a lock cylinder having a key-way, tumblers movably mounted in the cylinder with side portions thereof in alignment with the key-way, said tumbler side portions aligned with the key-way being medially cut away to provide key receiving recesses and end portions of the full width of the tumblers, and reinforcing beads formed on opposite 80 faces of each of the tumblers and extending longitudinally throughout the length of the tumblers to strengthen the connection between the end portions thereof.

5. A tumbler for locks comprising a substantially flat member having a key receiving recess at one side of its longitudinal axis, and a portion of enlarged thickness extending longitudinally throughout the length of the tumbler to increase the rigidity thereof. 95

6. In a lock cylinder, locking tumblers transversely movable in the cylinder, means for yieldably urging the tumblers in one direction, reinforcing ribs formed on opposite faces of the tumblers, and means whereby the reinforcing ribs of adjacent tumblers cooperate to hold the yieldable urging means. 105

7. In a lock cylinder having a key-way and an enlarged opening in communication with the key-way, a plurality of spaced tumblers movably mounted in said opening, springs for yieldably urging the tumblers in one direction, said springs being disposed between adjacent tumblers and within the enlarged opening, and means on the tumblers for holding the springs in position. 110

8. In a lock cylinder having a key-way and an enlarged opening in communication with the key-way, tumblers movably mounted in said opening, springs for yieldably urging the tumblers in one direction, said springs being disposed between adjacent tumblers and within the enlarged opening, and means on the tumblers for holding the springs in position, said last mentioned means serving to 115 strengthen the tumblers.

9. In a lock cylinder having a transverse opening provided with opposed guide-ways, tumblers having their side edges received in side guide ways, said tumblers being inserted 120

- into the opening from one end thereof, means for limiting movement of the tumblers in their direction of insertion, spring means abutting portions of the tumblers for yieldably urging the same in said direction, and means for holding the spring means against displacement and whereby the tumblers are retained in the cylinder.
10. In a lock cylinder having an enlarged transverse opening provided with opposed tumbler receiving guide-ways, tumblers slidably mounted in said guide-ways, means for limiting the movement of the tumblers in one direction, abutments on the tumblers projected laterally therefrom, abutments carried by the cylinder between the tumblers, and spring means confined between said abutments for yieldably urging the tumblers to their said limits of movement.
15. A tumbler for locks formed of substantially flat stock and provided with reinforcing ribs comprising a medial longitudinally extending portion of increased thickness to reinforce the same.
16. A tumbler for locks comprising a substantially flat member having a portion cut away to provide a key receiving recess, said recess dividing the member into intermediate and end sections, and a reinforcing rib comprising a portion of increased thickness extending longitudinally to connect the end sections.
17. In a lock, a plurality of spaced tumblers slidably guided at their edges in face to face relation, means for moving the tumblers, and means for guiding said moving means including grooves in the opposed faces of the tumblers.
18. In a lock, tumblers slidably guided at their edges in face to face relation, means for moving the tumblers, and means for guiding said moving means including grooves in the opposed faces of the tumblers, and ribs at the edges of the grooves.
19. In a lock cylinder, having tumblers slidably guided at their edges in face to face relation, spring means for moving said tumblers, and guide means for said spring means comprising ribs on the tumblers and a portion of the cylinder.
20. In a lock cylinder having a longitudinal key-way and a transverse tumbler receiving chamber, tumblers guided for movement in the transverse chamber, portions of the tumblers being cut away to form a continuation of the key-way, and springs for moving the tumblers, said springs being mounted in the chamber between the tumblers and beside the key-way.
21. In a lock cylinder, tumblers therein guided for movement crosswise of the cylinder, the cylinder and tumblers being recessed to provide a longitudinal key slot through the cylinder and tumblers, the larger transverse cross sectional dimension of said slot extending in the direction of movement of the tumblers, abutments on the tumblers, abutments carried by the cylinder between the tumblers, and springs located between the tumblers and beside the key slot, and confined between said tumblers and cylinder carried abutments for pressing the tumblers in one direction.
22. In a lock cylinder adapted to be produced by casting and having a transverse tumbler chamber therein, tumblers mounted in said chamber, said tumblers being arranged to provide a key passage along one side of the tumbler receiving chamber, and a ledge within the chamber formed as an integral part of the cylinder and projecting into the chamber from said side thereof for the full width of the key passage to provide a
5. A tumbler for locks formed of substantially flat stock and provided with reinforcing ribs comprising a medial longitudinally extending portion of increased thickness to reinforce the same.
10. A tumbler for locks comprising a substantially flat member having a portion cut away to provide a key receiving recess, said recess dividing the member into intermediate and end sections, and a reinforcing rib comprising a portion of increased thickness extending longitudinally to connect the end sections.
15. A tumbler for locks slidably guided at their edges in face to face relation, means for moving the tumblers, and means for guiding said moving means including grooves in the opposed faces of the tumblers.
20. In a lock cylinder having a transverse opening provided with opposed tumbler receiving guideways, tumblers disposed in said opening and guided for movement therein by the guide-way, means for limiting outward movement of the tumblers in one direction, spring means for yieldably urging the tumblers in said direction, and cooperating abutments carried by the tumblers and the cylinder and disposed between adjacent tumblers and between which the spring means are confined.
25. A die cast lock cylinder having a transverse tumbler receiving chamber entirely open at one end and having opposed guideways in its side walls, tumblers having their side edges slidably received in said guideways and inserted from said entirely open end, means for preventing movement of the tumblers out of the other end of said chamber, means for yieldably urging the tumblers toward said other end of the chamber, and means for maintaining the urging means within said chamber.
30. In a lock cylinder having a transverse tumbler receiving chamber, spaced tumblers slidably mounted in the chamber, means limiting movement of the tumblers out of the chamber in one direction, lugs carried by the tumblers and directed laterally from one face thereof, springs for the tumblers and engaging their lugs, and pin extending across the tumbler receiving chamber between the tumblers, between which and the lugs the springs are confined and whereby the tumblers are held against detachment from the cylinder.
35. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.
40. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.
45. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.
50. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.
55. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.
60. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.
65. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.
70. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.
75. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.
80. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.
85. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.
90. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.
95. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.
100. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.
105. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.
110. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.
115. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.
120. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.
125. In a lock cylinder having a transverse tumbler receiving chamber, spaced tumblers movably mounted in said transverse opening, springs for yieldably urging the tumblers in one direction, said springs being disposed between adjacent tumblers, and lugs struck from the sides of the tumblers and extended into the space therebetween to provide rests for the springs.

bottom for said passage and a support for a key insertable therein.

23. In a die cast lock cylinder having a transverse tumbler receiving chamber, a plurality of tumblers within the chamber, said chamber being slightly narrower than the width of the tumblers and the tumblers being retained in proper spaced relation by having their opposite edges slidable in 5 grooves formed in the sides of the chamber, the tumblers being cut away at one side to cooperate with the adjacent side of the chamber to provide a key passage at one side of the tumbler receiving chamber, and a ledge 10 15 within the tumbler receiving chamber comprising a plurality of projections extending into the chamber from said side thereof and between the tumblers for the full width of the key passage to provide a support for a 20 key insertable into the chamber to actuate the tumblers.

24. In a die cast lock cylinder having a transverse tumbler receiving chamber, the opposite side walls of which are provided 25 with channels to form guideways for tumblers, tumblers in said chamber having their side edges slidably engaged in said channels, said tumblers having key openings, opening to one side thereof to cooperate with the adjacent side wall of the tumbler receiving 30 chamber to form a key passage, and projections extended from said side walls of the chamber between the tumblers with certain of their surfaces aligned to form a bottom for 35 the key passage and support for a key inserted into said key passage.

In testimony whereof I have hereunto affixed my signature.

EDWARD N. JACOBI.
